TRUE RUNNING TABLE SLIDE

Filed Oct. 12, 1929

INVENTOR

EDWARD DAUB

WITNESS:
John A. McLowell

UNITED STATES PATENT OFFICE

EDWARD DAUB, OF LOS ANGELES, CALIFORNIA, ASSIGNOR TO EDNA A. SANDER, OF LOS ANGELES, CALIFORNIA

TRUE RUNNING TABLE SLIDE

Application filed October 12, 1929. Serial No. 399,310.

An object of this invention is to provide a table slide that is adapted to act directly and positively without lost motion or wobbling to move two sliding table top sections in opposite directions to exactly the same extent so that in case the slide is installed with the table top sections meeting at the middle of the table frame, and one of such sections is moved on such frame, such movement in 5 one direction will be exactly duplicated by the movement of the other table top section in the other direction.

Advantages are, perfectly smooth and even operation and absolute freedom from 10 sticking.

An object is to guard against difficulties due to swelling and warping.

Other objects are simplicity, and lightness and cheapness of manufacture and installation.

Another object is to practically provide against pulling apart or other displacement of parts while the device is attached to the table.

Another object is to provide a table slide construction that is made up of light castings and stampings of furniture sheet steel mounted on a guide bar that is preferably made of wood.

A broadly new, basic and pioneer feature of the invention is that there are provided in combination with each other a guide bar, slides movable endwise on the guide bar; and spur gears journaled to the guide bar 30 on parallel axes that are in fixed relation to each other.

I have provided in combination, a guide bar adapted to be fixed to a support, two racks parallel to the guide bar and adapted 40 to be fixed, respectively to the table top sections and two sets of shaft connected gearing carried by the guide bar and operating the racks respectively.

A feature of the invention is that I mount 45 the table top sections on racks that are supported by gears which are near the ends of the table so that as the table top sections are drawn to extend from the ends of the table frame, the weights of such sections are carried by the gears that operate the racks.

An advantage is that I avoid any side pull by arranging the parts so that the weight of the table top sections is directly applied to hold the racks in place on the spur gears that are in mesh with them respectively.

Preferably each table is provided with two guide bars including the mechanism and provision for attaching the device to the frame and the table top sections.

This invention includes the parts and combinations of parts hereinafter particularly described and claimed.

Other objects, advantages and features of invention may appear from the accompanying drawing, the subjoined detailed description and the appended claims.

The accompanying drawing illustrates the invention.

Figure 1 is a side elevation of a table slide constructed in accordance with this invention.

Fig. 2 is a view of the underside of the table slide shown in Fig. 1, all the parts being in set up position.

Fig. 3 is a section on line $\alpha\beta$, Fig. 2, and showing the slide attached to fragments of a table frame and one of the table top sections.

Fig. 4 is a broken perspective view of one of the rear racks, detached.

Fig. 5 is a detached section of the slide on line $\alpha\beta$, Figs. 1 and 2, and showing a clip holding parts together for shipping.

Fig. 6 is a top plan view of a table with the invention applied and with the table top sections drawn apart; one of said sections being broken away to expose the gearing connection of one corner of the installation.

The table slide comprises a guide bar 1 adapted for attachment to a table frame and provided with bearings 2 in which is journaled a shaft 3 having fixed to its ends bevelled gear wheels 4 that are respectively in mesh with the bevelled faces 5 of combination bevel and spur gears 6, the spur rims 7 of which are in mesh respectively with the sectional racks 8 which are preferably stampings of furniture sheet steel strips of Z shaped cross section having perforations in the form of slots 9 and adapted to mesh with

the spur gear, and adapted to be secured to the table top sections 10 by screws 11 through holes 12 in a flange 13 of the rack strip which is shown as comprising said flange 13 and a 5 flange 14 connected by the slotted web 15 and formed with cross bars 16 between the slots 9, and the end stop 17, wider than the respective bars, so that when the spur rim 7 approaches the end of the rack strip, a 10 tooth of the spur gear rim 7 strikes the stop and prevents the rack from further extending movement.

Preferably the bar 1 and the bearings 2 are wooden and the bearings are fixed to the 15 bar by screws 18.

The combination gears 6 are journaled on shafts comprising pins 19 fixed in sockets 20 in the guide bar 1, and said combination gear is anti-frictionally separated from the 20 bar by a washer 21.

The upper side of the bar is provided with a longitudinal groove 22, in which the flange 14 of the rack is slidably inserted while the table top securing flanges 13 are immovably 25 attached to the table top sections 10, respectively, so that when a table top section 10 is moved relatively to the table frame 23, to which the guide bar 1 is fixed, the spur gears and their shaft will be revolved and the 30 racks will be correspondingly moved endwise.

It is understood that the guide bar and the bearing 2 may be made of any suitable materials but it is at present deemed desirable 35 to make the guide bar and bearings of wood for cheapness, lightness and ease of manufacture.

The plain Z slide strips 24, correspond to the sectional rack strips 8, above described, 40 except that the rack structure is eliminated. The strips 8 and 24 are arranged to slide in the saw kerf grooves 22, 22' respectively that extend from end to end of the slide bar.

The slide bars are of various lengths for 45 various lengths of table; the length of the slide bars for any particular table depending upon the width of the opening provided between the table top end sections 10, to accommodate the maximum number of leaves 50 for which that particular table is intended.

In practice the parts will be assembled at the factory in a manner corresponding to that indicated in the drawing; there being provided a sheet metal packaging strip 25, having 55 its edges bent over to form grooves 26, into which the edges of the guide strips may be slid when the table slide is assembled as indicated in Fig. 5, thus to hold the parts together in a neat package for storing, transporting or marketing.

To install the slides on a table, the workman will first place the separable table top sections upside down on a flat surface with their meeting ends together, and after removing the clips 25, from the package as-

sembly shown in Fig. 6, will turn the table slide upside down in the desired position on the table top with the slide bar 1 supported by the Z strips and will then fasten to the table top section 10, the flanges which rest 70 thereon.

Then the workman will take the table frame 23, with its attached skirt 27 and legs 28, and will turn such frame upside down on the slides, and by means of screws 26, will fasten the frame to the guide bars as indicated in Fig. 3, and will then turn the table right side up, ready for use.

I claim:

1. A table slide comprising a guide bar having a groove along one side thereof and adapted to be fixed to a support; a bearing fixed to the bar and projecting from the grooved side thereof; a pair of combined spur and bevel gear wheels in journaled relation to the bar, mounted adjacent to said bearings respectively; a shaft journaled in the bearings parallel to the bar; bevel gears fixed to the shaft and meshing with the bevel gear wheels respectively; and combination runner racks adapted to be fixed to the table top sections, respectively, with their runners in the groove of the bar, and their racks meshed with the spur gears respectively.

2. A table slide comprising a slide bar provided with a groove along one side, a pin extending from said side of the bar, a spur gear journaled on the pin, a rack flange running in the groove and meshing with the gear, and means for fixing the rack to a table top section.

3. In a table slide, a sheet metal Z strip comprising a web and two flanges, one of its flanges being perforated to form a rack, and its other flange being adapted to be fixed to a table top section.

4. In a table slide, a rack comprising a strip and having orifices to receive the teeth of a spur gear, there being a series of transverse rack bars between said orifices and also having a transverse bar of greater width parallel to, and terminating the series of bars to stop the teeth of the spur gear to prevent endwise disengagement of the rack from the spur gear.

5. In combination, a guide bar adapted to be fixed to a support, two racks parallel to the guide bar and adapted to be fixed, respectively, to two table top sections, carried directly by the guide bars and two sets of shaft connected bevel gearing carried by the guide bar and operating the racks respectively.

6. The combination with a table frame, of bevel and spur gears which are mounted on the frame near the ends thereof; racks supported by the spur gears, and table top sections on the racks so that the weight of the table top sections is directly carried by the spur gears that operate the racks.

7. A device of the character set forth, comprising table top sections, a guide bar having a groove along one side thereof and adapted to be fixed to a support, shaft connected bevel 5 gearing carried by the guide bar, spur gears and racks in which the weight of the table top sections is directly applied to hold the racks in place on the spur gears that operate the racks.

10 In testimony whereof, I have hereunto set my hand at Los Angeles, California, this 28th day of September 1929.

EDWARD DAUB.
